ERNST HERKT, OF KIEL, GERMANY, ASSIGNOR TO FRIED. KRUPP GERMANIAWERFT
AKTIENGESELLSCHAFT, OF KIEL-GAARDEN, GERMANY.

SCAVENGING INTERNAL-COMBUSTION ENGINE.

Application filed April 3, 1926, Serial No. 99,510, and in Germany April 3, 1925.

- The invention relates to two stroke cycle double-acting internal combustion engines which are scavenged by means of ports. In scavenging such engines difficulties arise especially on the lower (piston rod) side of the cylinder, as here the piston rod forms an obstacle for a continuous course of the scavenging air current due to its unfavorable circular cross section.
- 10 The simplest and most satisfying scavenging effect would be attained with such engines by the adaption of the well-known so-called cross scavenging method, as illustrated in Fig. 1, with which method the scavenging air entering on one side of the cylinder A through admission ports C is directed into parallel with the cylinder wall by a baffle-plate b^1 provided on the piston, and after having struck the piston rod, 15 leaves the cylinder through exhaust ports D diametrically opposite to said admission ports C, as with this method the scavenging current strikes the piston rod but once, viz., at x . This method, however, suffers from some 20 drawbacks, in particular due to the baffle-plate b^1 which necessarily must be arranged on the end face of the piston and is undesired by certain reasons, and due to the forced double rectangular deflection of the 25 entering and escaping scavenging current, so that this method recently has been abandoned and the so-called reverse method, likewise well-known, has been adopted. With this method the scavenging air passes 30 the piston end face in a closed current, flows along the opposite cylinder wall up to the cylinder cover and returns on the entrance side where it escapes through exhaust ports which are situated on this side nearer to the 35 cylinder cover than the admission ports.
- 40 This scavenging method is illustrated in Figs. 2 and 3 as adapted to the piston rod side of the cylinder. This method, however, shows from the first the drawback of the scavenging current striking the piston rod on two places, viz., at x and y , Fig. 2. It has been proposed, therefore, in order to attain in some measure, at least on the piston end face, a shockless passage of the scavenging current, to so direct the admission ports, 45 see Fig. 3, that the scavenging air will not strike the piston rod directly and the branch currents unite again on the opposite side and ascend and so on. This measure, however,
- is likewise not capable of securing a continuous and eddiless course of the scavenging current. For, as clearly will be seen from Fig. 3, the branch currents entering the cylinder through the group of ports c^1 , meet the branch currents introduced through the group of ports c^2 under a rather large angle, this causing disturbing eddies to arise behind the piston rod. Furthermore, this scavenging method has the drawback of the entering and escaping scavenging currents closely passing each other in counter-current on the admission and exhaust ports. In consequence thereof violent eddies will arise on this place too, causing the admitted fresh scavenging air to be immediately withdrawn again from the cylinder, a loss in scavenging air thus being unavoidable.
- 55 Now my invention has for its object to create a scavenging means, in particular adapted to be used on the piston rod side of two stroke cycle double-acting internal combustion engines, by means of which the above-mentioned drawbacks are obviated and the scavenging air current must pass the piston rod but once, as in the cross-scavenging method shown in Fig. 1.
- 60 An embodiment of the subject-matter of my invention is illustrated by way of example in the drawing which accompanies and forms part of this specification.
- 65 In this drawing:
- 70 Figs. 1 and 2, are vertical sections in diagrammatic form of 2 forms of piston and cylinder arrangement according to the prior art.
- 75 Fig. 3 is a cross section of line 3—3, of Fig. 2.
- 80 Fig. 4 is a fragmentary longitudinal section through the working cylinder of an internal combustion engine,
- 85 Fig. 5 is the cross section on line 5—5 of Fig. 4,
- 90 Fig. 6 is the cross section on line 6—6 of Fig. 5.
- 95 A denotes the working cylinder of a two stroke cycle double-acting internal combustion engine and B the piston reciprocating therein and having an end face b^2 tapering towards the piston rod E. I provide a group of admission ports C on both sides of cylinder A and a group of exhaust ports D, 100 said ports C, D being situated on a common level. Both said groups of ports are in 105

clined in the direction of the angle of the tapered piston end face b^2 , see Fig. 4, the exhaust ports D penetrating the cylinder wall in radial direction, see Fig. 5, while 5 the admission ports C are arranged so as to cause the branch currents entering there-through to arrive behind the piston rod.

By the described arrangement and direction of the admission and exhaust ports C, 10 D in combination with the described shape of the piston end face b^2 I attain that the branch currents entering through the admission ports C are guided, after having passed these ports, by the tapered piston end face 15 b^2 within the cylinder up in the manner shown in Fig. 4, and unite, without any formation of eddies, so as to form a closed scavenging current which rises along the cylinder wall, branches near the cylinder 20 cover so as to embrace the piston rod, there-upon is guided downwardly in a closed condition along the opposite cylinder wall and finally is deflected by said tapered piston end face b^2 so as to continuously escape 25 through the exhaust ports D. I attain in this manner that the scavenging air entirely obviates the obstacle formed by the piston rod and meets it but once, viz., on the cylinder cover, as in the well-known scavenging 30 method illustrated in Fig. 1. I further attain that the scavenging air is guided satisfactorily and continuously during the whole scavenging period and leaves the cylinder in

a quietly flowing current, all portions of the cylinder being met by the scavenging air. 35

Of course the generatrix of the tapered end face b^2 of the piston might be formed by a suitable curve the curvature of which, however, must subside in a continuous course into the line of inclination of the admission 40 and exhaust ports.

I claim:

Two cycle internal combustion engine of the Diesel type, comprising a cylinder, a piston working therein having a piston rod penetrating the cylinder room and an end face tapering towards the piston rod, piston controlled inlet ports arranged at both sides of the cylinder and outlet ports arranged at one side of the cylinder between the inlet ports and at the same level with the inlet ports, said inlet ports being inclined so that the incoming scavenging air flows tangent 45 the tapered end face of the piston on both sides and strikes the cylinder wall opposite to the outlet ports, the two flows of the scavenging air uniting and being directed along said wall to the cylinder head crossing the piston rod and flowing to the outlet ports, said outlet ports being inclined at the same 50 angle as the tapered face of the piston rod.

The foregoing specification signed at Hamburg, Germany, this twenty-fifth day of February, 1926.

ERNST HERKT.
